UNITED STATES PATENT OFFICE

LLOYD F. SCHRADER, OF RICHMOND HILL, NEW YORK, AND WILLIAM H. WRIGHT, OF MOUNTAIN LAKES, NEW JERSEY, ASSIGNEES TO FOUNDATION OVEN CORPORATION, OF NEW YORK, N. Y.

COMBINATION OVEN

Application filed January 12, 1929. Serial No. 332,151.

This invention relates to improvements in coke oven construction and aims to provide a structure of improved design so arranged that the gas and air regenerators are located substantially in vertical alignment. The design is such that the coke chambers are located between heating walls having combustion flues therein. The heating walls are sustained by supporting walls located in vertical alignment therewith, these supporting walls having ducts therein for conveying gas and air from the respective regenerators. The regenerators are located one over the other between the supporting walls and a duct, for carrying the incoming gas or outgoing spent products of combustion, is provided which extends the entire length of the regenerators and to the outer faces of the structure. This duct permits of ready access to the division wall between the gas and air regenerators for inspection or sealing. In order that the invention may be fully understood a preferred embodiment thereof is illustrated in the accompanying drawings forming part of this specification.

In the drawings—

Fig. 1 is a transverse section through the coke oven the section being taken through a coking chamber and the regenerators lying below it;

Fig. 2 is a similar section in a plane parallel to the plane of Fig. 1 but taken through the heating walls and supporting walls;

Fig. 3 is a staggered section taken approximately on the line 3—3 of Fig. 1;

Fig. 4 is an elevation view from the left side of Fig. 1;

Fig. 5 is a sectional elevation taken on the line 5—5 of Figs. 1 and 3;

Fig. 6 is a similar sectional view taken on the line 6—6 of Figs. 1 and 3;

Fig. 7 is an enlarged detail view of the lower portion of Fig. 5.

Referring in detail to the drawings 10 represents the coke oven as a whole which is supported on a foundation 12 in which flues 14 and 16 are provided for carrying off the waste gases to a suitable stack not shown.

Gas and air regenerator chambers 18 and 20 are provided which as shown are disposed

in vertical alignment with one another. Between the gas regenerators are supporting walls 22. These walls are in substantially vertical alignment with heating walls 26. The lower portions of the supporting walls 22 between the air regenerators, as most clearly shown in Fig. 7, may be greater thickness than the portions of said supporting walls between the gas regenerators. The heating walls 26 enclose the oven chambers 28 which are adapted to receive the material to be coked. These oven chambers are closed at their opposite ends by suitable doors 30 of the usual construction.

Between each gas regenerator 18 and its companion air regenerator 20 we provide a duct 32 which extends substantially the full length of the regenerators. Over the top of each air regenerator is a partition wall 34 formed of flat bricks which are supported on the corbeled supporting bricks 36 forming the upper parts of each air regenerator. This flat partition wall 34 can be sealed tight by placing over the joints pulverized material of sufficient fineness, a suitable material being finely ground fine clay or silica cement. Over the partition wall 34 we preferably place a layer of insulating brick material as indicated at 35. This material is placed so as to provide channels for holding the fine sealing material 37 above the joints of the division wall.

Air ducts 38 are formed in the supporting walls 22 and these ducts for the greater part of their length coincide with the center line of said supporting walls. Each duct 38 has at its lower end a flared mouth 40 which opens into one of the air regenerator chambers 20. The ducts 38 at their upper ends open into the combustion flues 40 formed in the heating walls 26. Also opening into each combustion flue 40 there is a duct 42 located substantially centrally of supporting wall and having a flaring mouth 44 which opens into a respective gas regenerator 18.

The air and gas ducts 38 and 42 respectively are so arranged that alternate combustion chambers 40 communicate with the same respective gas regenerator. Similarly alternate flues communicate with the same re-

spective air regenerator. In other words adjacent combustion flues communicate with different regenerators.

The several combustion flues formed in the heating walls are separated from one another by flue walls 46. These walls, as best shown in Fig. 3, are thickest at the center and taper in thickness as they approach the adjacent coking chambers.

Gas for combustion is supplied by a gas main 48 through branch pipes 50 under control of suitable valves 51 of known construction. This gas passes through the gas regenerators and absorbs heat from the checker-work therein. This gas flows through ports 42 to the combustion flues where it meets air which has been passed through the regenerators 20 and preheated. The air and gas mix in certain combustion flues 40 and flow upwardly and the products of combustion pass through ports 50 at the tops of alternate combustion flues and said products flow downwardly through alternate regenerators and give up their heat the gases being finally passed through the tunnel flues 14 and 16 to a suitable stack, not shown. Any suitable reversing valve mechanism of known construction may be employed for controlling the gas flow and as this mechanism forms no part of the present invention it is not shown nor will it be further described.

In supplying gas directly to the combustion chambers without passing it through the regenerators we provide so-called gas guns 54—54 which are connected with the fuel supply main 48 the flow of gas from said guns being under control of a valve 56.

The guns 54—54 communicate with gun ducts 60—60 arranged symmetrically on opposite sides of the vertical air ducts 38. In other words these gun ducts spaced equally on opposite sides of the center line of the supporting walls. Each gun duct 60 has a port 62 extending upwardly and opening into an alternate combustion flue 40.

When the guns 54—54 are arranged as described we are enabled to place buckstays 58 on the outer faces of the coke oven in alignment with the centers of the heating walls as clearly shown in Fig. 3.

The structure described has certain advantages over prior coke oven practice which may be briefly summarized as follows. By providing the air and gas regenerators in vertical alignment with one another directly below the oven chambers we require only one supporting wall under each heating wall. The provision of air and gas ducts in the supporting walls between the regenerators and the location of combustion flues centrally of the heating wall enables the placement of the gas guns in such location that we can use straight buckstays without splices located centrally of the heating walls.

Owing to the fact that the gas and air

regenerators are located one above the other the full width under each oven is available for the accommodation of such regenerators. This arrangement also provides sufficient space so that ducts leading from the gas and air regenerators can be of a generous area in cross section. Thus there is less resistance to the flow of gases through the system as compared with typical designs in which the crowding in of ducts in a limited space necessitates the use of restricted areas with the resultant resistance to flow. The flow resistance through the checker brick in a low, broad regenerator is less than in a narrow, high regenerator. A further advantage in this relationship is also that there is in a high narrow regenerator a greater tendency for the gases to channel up between the checker filling and the regenerator wall than in a broad, low regenerator.

It is also a fact that for a given distance between the centers of ovens and a given height devoted to regenerators we can accommodate more checker material than is possible in the design employing a vertical division wall between regenerators. The wider regenerators are made possible for given size of oven chambers when the same are placed one above the other and this enables the use of a standard length brick for construction of the checkerwork. The provision of flat partition walls with a duct between the respective gas and air regenerators gives access for repair or sealing of the regenerator division wall. The placing of gas and air regenerators one over the other reduces the number of regenerator division walls and makes a corresponding reduction in the number of buckstays required.

With the former construction having separate division walls between the regenerators it was usually found necessary to provide additional intermediate buck-stays below the oven floor to hold the ends of such walls. Our improved construction eliminates such intermediate supports. By providing a supporting wall which is thicker at the bottom than at the top an advantageous distribution of material relative to the total load is secured.

The importance of the above advantages will be readily apparent to those skilled in this art.

While we have described quite specifically the details of the embodiment of the invention illustrated it is to be understood that various modifications may be made by those skilled in the art without departing from the invention as defined in the appended claims.

We claim:

1. A coke oven comprising a series of alternating coking chambers and heating walls therefor arranged laterally of each other in a row, each of said heating walls comprising a row of combustion flues, supporting walls

for said heating walls below the same having up-take and down-take ducts therein for supplying gas and air to and taking combustion products from said combustion flues at intervals along the lengths of said heating walls, a gas regenerator and an air regenerator in superposed relation to each other between each two of the adjacent supporting walls and each of the regenerators communicating with one of said ducts.

2. The coke oven structure of claim 1 wherein the up-take and down-take ducts in each of the supporting walls are formed substantially along a vertical plane in and median and longitudinal of the wall and provided with laterally extending mouths opening into part of said regenerators.

3. The coke oven structure of claim 1 wherein the up-take and down-take ducts in 20 said supporting walls are provided with laterally extending mouths opening into said regenerators and a pair of gas gun conduits formed in the upper portions of each of said supporting walls, the members of a pair of 25 said gas gun conduits lying on different sides of each of the up-take and down-take ducts in the wall, the said gas gun conduits communicating with said combustion flues.

4. The coke oven structure of claim 1 30 wherein the up-take and down-take ducts in each of the supporting walls are formed substantially along a vertical plane in and median and longitudinal of the wall and provided with laterally extending mouths opening 35 into part of said regenerators and a pair of gas gun conduits formed in the upper portions of each of said supporting walls and communicating with the combustion flues in the heating wall thereabove, one gas gun 40 conduit of each of the pairs lying on a different side of one of said ducts from its mate and buckstays for each of said supporting walls and said heating walls at the lateral ends thereof, each of said buckstays lying 45 between the members of a pair of said gas gun conduits.

5. The coke oven structure of claim 1 50 wherein the lower portion of each of the supporting walls is thicker than an upper portion thereof between the upper regenerators.

In witness whereof, we have hereunto signed our names.

LLOYD F. SCHRADER.
WILLIAM H. WRIGHT.
